UNITED STATES PATENT OFFICE.

RAFAEL VACHIER, OF BATON ROUGE, LOUISIANA.

FILTERING APPARATUS FOR USE WITH SACCHARINE SOLUTIONS.

Application filed June 8, 1921. Serial No. 475,996.

To all whom it may concern:

Be it known that I, RAFAEL VACHIER, a citizen of the United States, residing at Baton Rouge, in the parish of East Baton Rouge, Louisiana, have invented certain new and useful Improvements in Filtering Apparatus for Use with Saccharine Solutions; and I do hereby declare the following to be a full, clear, and exact description of the invention, such as will enable others skilled in the art to which it appertains to make and use the same.

My invention relates to improvements in filtering apparatus as used in the manufacture of sugar or syrup from cane or beets, or other sucrose yielding plants. It is more especially adapted for use in the treatment of raw juice from the cane mill, but it may be used in the further filtering of the partially evaporated syrup in either the sugar factory or the sugar refinery, and is applicable to use in the manufacture of either cane, beet, or other sugars or syrups where made in large enough quantities to justify the construction of an apparatus to carry out the invention hereinafter described.

The invention may be used either to filter the saccharine solution, or to decolorize the same, or for both purposes as will be more fully described.

My invention will be more clearly understood after reference to the accompanying drawings, in which like parts are indicated by similar reference symbols throughout the several views, and in which:—

Figure 1 is a diagrammatic view showing in elevation a complete apparatus illustrating two of the filter units.

Figure 2 shows a side elevation, on a larger scale, of one of the filter units, parts being broken away.

Figure 3 is an end view of the device shown in Figure 2, as seen from the left of said figure.

Figure 4 is an end view of the device shown in Figure 2 as seen from the right of said figure.

Figure 5 shows a section along the line 5—5 of Figure 2, and looking in the directions of the arrows.

Figure 6 is a plan view of the device shown in Figures 2 and 3, with the cover removed.

Figure 7 shows a section along the line

7—7 of Figure 5, and looking in the direction of the arrows, the parts being shown on a larger scale.

Figure 8 is a fragmentary view showing a section along the line 8—8 of Figures 2 and 6, but on the same scale as shown in Figure 7.

Figure 9 is a detail showing in front elevation one of the filter leaves used in the apparatus, and

Figure 10 shows a section along the line 10—10 of Figure 9, and looking in the direction of the arrows.

Since the desired result depends more especially upon the construction and operation of the individual filter units, it will be more convenient to describe in detail one of these units, the construction of all of said units being substantially identical, before attempting to describe the operation of the complete apparatus.

The construction of the entire filter unit is shown in the assembled relation in Figures 2 to 6, and details of same are shown in Figures 7 to 10, while the complete apparatus is shown diagrammatically in Figure 1.

A represents the tank in which the various filter leaves and the parts co-operating therewith are mounted. This filter tank is preferably provided with a rounded bottom *a* and vertical sides *a'* flanged at the top, as at *a''*. One of the ends of the filter tank is closed with a plate *A*², which is preferably slotted, as at *a'*, see Figure 4, to permit the insertion of a tubular shaft *E*, as will be hereinafter described.

The other end of the filter tank is closed with a plate *A'*, and the top of the tank is securely closed against pressure by means of the cover *B* and bolts *C*. Any suitable packing could, of course, be used. The slot *a'* of the end plate *A*² may be closed in any convenient way, as by means of the gate *D* and securing members *D'*, see Figure 4.

The tank may be supported in any convenient manner, as by suitable feet *A*³, and the tank is also preferably provided with longitudinal plates mounted exterior to and along the sides thereof, as shown at *A*⁴ and *A*⁵, see Figures 2, 3 and 4.

The tubular shaft *E* is connected, as by means of the pipe *F*, shown in dotted lines at the right in Figure 2, to any suitable source of water supply, as will be hereinafter

described. The other end of this tubular shaft is closed, as at e , and this closed end carries a gear wheel E' which meshes with a pinion G on the stub shaft G' , see Figures 5 3 and 6. This stub shaft may be driven in any suitable way, as by means of the pinion G^2 , see Figures 1 and 6, and the belt G^3 , see Figure 1.

Mounted on the tubular shaft E are a 10 series of filter leaves H , as shown in Figures 2 and 6 and in detail in Figures 9 and 10. These filter leaves H consist of the U-shaped frames H' to which are attached the foraminous sheets H^2 and H^3 , as by means of the 15 rivets h , see Figures 9 and 10.

These foraminous sheets H^2 and H^3 may be made of suitable fine-mesh metal wire or perforated metal, which is not apt to corrode, such as certain well known nickel 20 alloys. In order to slide these leaves onto or remove the same from the tubular shaft E , I provide central bearings, as shown in Figures 9 and 10, which comprise the middle ring I and the outer rings I' , which are 25 connected together by the bolts or rivets i and form a tight joint with the edges of the sheets H^2 and H^3 . The individual leaves are connected at the top by the butt plates J to the pipes K , which are perforated at 30 their bottom, as at k , with one end closed as at k' and the other end open as at k^2 , and screw-threaded, as at k^3 , see Figure 10, to receive the cock k^4 . Thus any liquid forced between the foraminous sheets H^2 and H^3 35 will tend to flow up into the pipe K , and may be drained off through the cock k^4 . The ends of the pipes K , which project from the filter leaves, rest upon suitable supports L , see Figures 5 and 6, which are provided 40 in the interior of the tank A . On the exterior of the tank, I provide the trough M to receive the filtered liquid, which trough is preferably provided with a partition m , separating it into two troughs, one of which 45 is drained by the pipe M' , see Figures 3 and 5, and the other of which is drained by the pipe M^2 . The liquid may be deflected from the various cocks k^4 into either side of the partition m by means of a suitable deflecting plate M^3 , which may be 50 turned to engage either one or the other of the stops m' or m^2 , see Figures 3 and 5.

The tubular shaft E is provided with a series of screw-threaded openings e^0 to engage the screw-threaded ends p of the spray pipes P , which pipes are adjustably mounted in place by means of the nuts P' , see Figure 8. These spray pipes P are provided with a series of spray openings, such 55 as the slots p^0 , see Figures 7 and 8, and fastened to these spray pipes are brackets Q secured to the pipes P by the straps Q' and bolts q , as shown in Figure 5, and in detail in Figure 7. These brackets Q carry 60 65 the scraping blades R and S , see Figures

5 and 7, and the pipes P with the brackets Q and the blades R and S are rotated between adjacent leaves in either clockwise or anti-clockwise direction, as will be hereinafter more fully described.

The scraping blades R and S are adjustably mounted on the brackets so as to be closer to or further from the base of the filter leaf for reasons that will be hereinafter described.

Each filter unit is provided with a manifold N at the bottom thereof which may be used for charging or for emptying the filter tank, or for washing out same, as will be hereinafter described.

Compressed air may be supplied to the upper part of the filter tank by means of the pipe T controlled by the valve t and, similarly, compressed air may be supplied to the lower part of the filter tank by means of the branch pipe T' , controlled by the valve t^0 , and perforated branches T^2 , as shown in Figures 1, 2, 4 and 6.

Referring now to the diagram of the complete apparatus shown in Figure 1, U represents the motor, which is preferably an electric motor and drives the power shaft U' , which shaft drives the various moving parts of the apparatus, such as the force pumps V and V' and the belts G^3 . Suitable clutch mechanisms are provided, where required, such as are shown at U^2 and U^3 .

The force pump V for supplying water for the flushing system is connected to any suitable source of water supply not shown, and delivers water under pressure through the flushing main F . There should be one of these force pumps V for each filter unit, one only being shown in Figure 1.

W is an overhead tank to receive the raw juice which is located at a sufficient height to permit the liquid to be filtered to flow down in the apparatus under sufficient pressure. This tank W is connected by the pipes W^0 and W' and W^0 and W^2 , respectively, to the manifold N of the first filter unit, and the pipe W^2 is connected by the pipe W^3 to the manifold N of the second filter unit, and so on indefinitely, only one overhead tank W being needed to supply the raw juice to any desired number of filter units. Of course, suitable valves will be provided wherever needed in the apparatus to control the flow of liquid through the various pipes, passages, or receptacles, for liquid.

The pipe W' is also provided with a branch pipe W^4 to draw off any desired quantity of liquid to the mixing chamber X , where the finely divided filtering material is mixed in as will be hereinafter described. The liquid from the mixing chamber X may be carried by the pipes X' and X^2 to the manifold N of the first filter unit, and by the pipes X' and X^3 to the man-

ifold of the second filter unit, and similarly to as many additional filter units as may be provided in the system.

The filtered liquor from each filter unit 5 is carried from the trough M by the pipe Y to the pressure pump V' whence it is forced through the pipe Y' to the overhead tank Z, whence it flows through the pipe Z' to the manifold N of the second filter unit.

10 The manifold N of each filter unit is provided with a waste pipe N' connected to the ditch or sewer, and with a pipe N² for supplying hot water, and a pipe N³ for supplying live steam.

15 Having thus described the details of the apparatus comprising a system composed of two filter units, I will now proceed to describe the operation of the system, it being understood that the number of filter units 20 may be, within limits, increased indefinitely.

The apparatus is adapted to be used either to first filter the raw juice and then de-colorize and filter the liquid coming from the first filter unit; or it may be used to filter 25 and de-colorize the saccharine solutions formed at any of the earlier stages incident to the manufacture of the sugar.

The use of the apparatus in the filtering of raw juice and the subsequent filtering and 30 de-colorizing of the juice from the first filter unit will first be described.

The raw juice from the mills is supplied from the heaters, not shown, to the overhead tank W through the pipe W'.

35 In beginning the operation on each filter unit, a portion of this juice is drawn off through the pipe W' into the mixing chamber X where it is thoroughly mixed with an excess of a suitable porous filtering medium, such as kieselguhr, or the like; and the mixture holding the filtering medium in suspension is conveyed through the pipes X' and X² and the manifold N of the first filter unit to the filter tank above the manifold;

40 the liquid flows upwards between the filter leaves, and the porous filtering medium forms a film or thin cake over the filtering surfaces, thus "pre-coating" the filter frames.

Now the raw juice is turned on through the 45 pipe W' and flowing in the filter tank under pressure it passes through this film, leaving most of the solid particles caught by the film; while the filtered liquid flows from the interior of the filter frames upwards and out 55 through the pipes K, and escaping through the faucets k⁴ enters the trough M. The plate M³ deflects the liquid from the faucets into the proper side of the trough M according to whether the liquid is running 60 muddy, as will occur in the initial stages, or clear, as will result after the filter leaves are properly operating. If any particular faucet fails to run clear, that faucet may be closed, thus shutting off the action of the 65 corresponding filter frame.

The filtered liquid runs from the trough M through one or the other of the pipes M' or M², and is carried by the pipe Y to the force pump V', and is forced through the pipe Y' to the overhead tank Z, where it is 70 mixed with any suitable de-colorizing agent, such as one of the various kinds of carbon used for the purpose, and then it is carried by gravity through the pipe Z' to the manifold N of the second filter unit.

75

The filtered liquid flows as a clear liquid from the second unit, and therefrom a high grade white sugar may be ultimately manufactured in the usual way.

When the liquid starts to run slowly at the 80 faucets the filter unit has done its work, and is ready to be cleaned out.

Incident to the cleaning-out operation, compressed air is turned on through the pipe T; this displaces the juice left in the cake, 85 which runaway juice is "blown back" to tank W through the pipe W'.

The next operation is the "sweetening off" of the cakes. Warm water at 20-30 lbs. pressure is allowed to flow in through the 90 pipe N² and out of the faucets until the escaping liquid does not taste sweet any longer; after which the supply of warm water is shut off.

Then comes the final operation, the "flushing out" or true cleaning of the mud cakes; the mechanism for rotating the hollow shafts E being turned, the scrapers start to tumble down the cakes; at the same time water at 75 to 100 lbs. pressure is turned on to the fluid 100 pressure main F and flows into the hollow shaft E, out of the small flushing pipes radiating therefrom, washing out the particles of mud or the like left on the filter frames; and the mixed mud and water flow 105 out of manifold N through the waste pipe N'.

Thus we complete the pure filtering process in four stages:

- (a) Precoating and filtering,
- (b) Blowing-back,
- (c) Sweetening-off,
- (d) Flushing out.

In the second process or de-colorization of the filtered juice, the bright juice obtained 115 from the first filter unit is drawn by the turbine pump V' through the pipe Y, and is forced through the pipe Y' to the tank Z located at a convenient height (to produce 20-30 lbs. pressure), where the required 120 amount of decolorizing char is added and intimately mixed with the liquid, after which the liquid flows through the second filter unit in the same fashion as was done in the first. After this second filtration the 125 juice comes out not only bright but decolorized, thus filling the two essential requisites to produce "standard granulated sugar."

The second filter unit, however, differs from the first in that the scrapers primarily 130

are set a further distance from the frames than in the scraping operation, and are kept constantly moving (backwards) so as to form a carbon cake of constant thickness. 5 When the char is "spent" and it does not further decolorize, the char-cake is to be removed from the filter, but it should first be "blown-back" and sweetened-off, as in the case of the first filter unit, after which the 10 mechanism is turned on (forward) to tumble down the char-cakes, and at the same time the high pressure water turned on to flush out any adhering particles of char on the frames. The operation is more or less 15 continuous and may be repeated indefinitely.

Where it is desired to treat saccharine solutions other than raw juice, such, for instance, as syrup in the process of refining, the operation is substantially similar to that 20 referred to in connection with the second step of treating the raw juice, that is the mechanical filtering medium such as kieselguhr, or the like may be omitted, a portion of the syrup to be de-colorized and filtered 25 may be first treated with the de-colorizing agent, such as one of the various forms of carbon, and formed into a cake or film on the filter frames, after which the syrup is forced through this film under pressure and 30 comes out a clear de-colorized liquid.

Incident to this operation the scrapers should be continuously run backwards as before described, stirring up the mass, and keeping a uniform thickness of de-colorized 35 film on the filter frames and smoothing off the same, and when the operation is completed in any filter unit that unit is blown back, sweetened off and flushed out, as previously described.

40 In the operation of cleaning out the filter unit the scrapers are run in the forward direction, causing the char to tumble down as before described. In this second operation it will not be necessary to have the scrapers 45 as close to the filter frames as at first, where large quantities of mud and other foreign properties had to be removed. These scrapers can be initially set at the desired distance from the corresponding filter frame 50 by giving the brackets Q a slight lateral tilt relative to the spray pipes P. This adjustment, of course, would have to be made before the filter frames are assembled on the shaft E. In order to provide for the 55 smoothing effect when rotated in one direction, or for the scraping effect when rotated in the opposite direction, the scrapers R are preferably curved outwards, as shown at r in Fig. 7.

60 During the operation compressed air may be admitted through the pipes T² to keep the liquid well stirred up and to hold the particles of filtering or decolorizing material in suspension therein.

In order to assemble the parts, suppose the 65 filter tank A to be empty, except for the air pipes T' and T², and suppose the several parts carried by the rotating shaft to be in the dis-assembled relation.

The spray pipes and filter frames are alternately mounted on the hollow shaft E in the general relation shown in Figure 6. Each spray pipe P is screwed into the shaft E as shown in Fig. 8, and is set at the desired inclined position by means of the lock 70 nut P' so that the scrapers will be at the proper distance from the adjacent filter frames. The first filter frame is next slipped in place over the end of the shaft E, then the next pair of spray pipes, then the next 75 filter frame, etc., until the shafts E, with the spray pipe fastened thereto, and the filter frames mounted thereon, become a complete structure such as shown in Fig. 6. This structure is then lifted as a whole into the 80 filter tank, and one end of the tubular shaft E is secured to the stub shaft E², as shown in Fig. 6, and the other end of the shaft E is lowered through the slot a⁰ in the opposite head of the filter tank, and is revolvably 85 mounted opposite the end of the flushing main F, shown in Fig. 2.

The plate D is secured in place by means of the clamps D', the top B of the filter tank is put in place, and made air-tight by 90 means of the bolts C, and the apparatus is ready for use.

In order to dis-assemble the parts, remove the top B of the filter tank, remove the filter plate D and the clamps D', disconnect the inner end of the shaft E and hoist the shaft E with the parts carried thereby 100 out of the tank, when the filter frames and spray pipes may be removed for purposes of cleaning, or repair, or renewal.

105 Thus it will be seen that the filter frames, spray pipes, etc. can be lifted bodily together with the shaft E out of the filter tank and will be conveniently accessible for renewal or repair.

110 With the herein described arrangements, it will be unnecessary to use filter bags or the like, as these are very troublesome, are apt to wear out or leak, and prove very unsatisfactory in practice.

115 It will be obvious that various modifications might be made in the herein described apparatus, and in the construction, combination and arrangement of parts which could be used without departing from the spirit of the invention; and I do not mean to limit the invention to such details except as particularly pointed out in the claims.

120 Having thus described my invention what I claim and desire to secure by Letters Patent of the United States is:

1. A filler unit for use in apparatus of the character described comprising a closed

- 5 tank, a hollow tubular shaft revolvably mounted in said tank, a series of filter frames removably supported in said tank and loosely mounted upon said shaft and spaced apart thereon, a series of laterally perforated spray pipes radially mounted on said shaft and projecting between said frames, scrapers mounted on said spray pipes, means for rotating said shaft when desired, and means for supplying flushing fluid to the interior of said shaft.
- 10 2. A filter unit for use in apparatus of the character described comprising a closed tank, a hollow tubular shaft revolvably mounted in said tank, a series of filter frames removably supported in said tank and loosely mounted upon said shaft and spaced apart thereon, a series of laterally perforated spray pipes radially mounted on said shaft and projecting between said frames, scrapers carried by said spray pipes, means for adjusting the distance between each scraper and the adjacent frame, means for rotating said shaft when desired, and means for supplying flushing fluid to the interior of said shaft.
- 15 3. A filter unit for use in apparatus of the character described comprising a closed tank, a hollow tubular shaft revolvably mounted in said tank, a series of filter frames removably supported in said tank and loosely mounted upon said shaft and spaced apart thereon, a series of laterally perforated spray pipes radially mounted on said shaft and projecting between said frames, scrapers mounted on said spray pipes, means for rotating said shaft either clockwise or counter-clockwise as desired, and means for supplying flushing fluid to the interior of said shaft.
- 20 4. A filter unit for use in apparatus of the character described comprising a closed tank, a hollow tubular shaft revolvably mounted in said tank, a series of filter frames removably supported in said tank and loosely mounted upon said shaft and spaced apart thereon, a series of laterally perforated spray pipes radially mounted on said shaft and projecting between said frames, scrapers carried by said spray pipes, means for adjusting the distance between each scraper and the adjacent frame, means for rotating said shaft either clockwise or counter-clockwise as desired, and means for supplying flushing fluid to the interior of said shaft.
- 25 5. A filter unit for use in apparatus of the character described comprising a closed tank, a hollow tubular shaft revolvably mounted in said tank, a series of filter frames removably supported in said tank and loosely mounted upon said shaft and spaced apart thereon, each filter frame comprising a pair of foraminous sheets of metal spaced apart, with a supporting pipe secured in the upper end of the frame and provided with perforations in its lower side and with a drain cock at one end thereof, a series of laterally perforated spray pipes radially mounted on said shaft and projecting between said frames, means for rotating said shaft when desired, and means for supplying flushing fluid to the interior of said shaft.
- 30 6. A filter unit for use in apparatus of the character described comprising a closed tank, a hollow tubular shaft revolvably mounted in said tank, a series of filter frames removably supported in said tank and loosely mounted upon said shaft and spaced apart thereon, each filter frame comprising a pair of foraminous sheets of metal spaced apart, with a supporting pipe secured in the upper end of the frame and provided with perforations in its lower side and with a drain cock at one end thereof, a series of laterally perforated spray pipes radially mounted on said shaft and projecting between said frames, scrapers mounted on said spray pipes, means for rotating said shaft when desired, and means for supplying flushing fluid to the interior of said shaft.
- 35 7. A filter unit for use in apparatus of the character described comprising a closed tank, a hollow tubular shaft revolvably mounted in said tank, a series of filter frames removably supported in said tank and loosely mounted upon said shaft and spaced apart thereon, a series of laterally perforated spray pipes radially mounted on said shaft and projecting between said frames, scrapers mounted on said spray pipes, means for rotating said shaft when desired, means for supplying flushing fluid to the interior of said shaft, and means for supplying compressed air to the interior of said closed tank.

RAFAEL VACHER.
